UNITED STATES PATENT OFFICE.

EDWARD W. COUGHLIN, OF NEW DORP, NEW YORK, ASSIGNOR TO INTERLOCKING RAIL JOINT CORPORATION, A CORPORATION OF NEW YORK.

RAIL-JOINT.

1,281,333.

Specification of Letters Patent. Patented June 26, 1917.

Application filed November 12, 1914. Serial No. 871,647.

To all whom it may concern:

Be it known that I, EDWARD W. COUGHLIN, a citizen of the United States of America, residing at New Dorp, Richmond county, Staten Island, New York, have invented certain new and useful Improvements in Rail-Joints, of which the following is a specification.

My invention relates to rail joints.

10 In such joints as now generally constructed, the contiguous ends of the rail sections are secured together by means of angle bars, one at each side of the web of the rail, these bars being fastened to the rail section by bolts. The purpose is to join the ends together as closely as possible to prevent separation and relative movement of the rail sections.

20 The construction of the angle bar now in general use tends to maintain the surface of the rail sections in a straight line. The settlement of ties under the weight of the passing wheels destroys this construction and produces great bending stresses in the angle bars. These stresses are proportional to the amount of settlement of the supporting tie or ties, and frequently cause fracture of the angle bars.

30 By reason of this wear, the angle bars become loose and refuse to perform their functions; the pounding of wheels at the joint becomes more pronounced and the stresses within the material of the joint bars rapidly increase. To obviate this condition constant watching is necessary, and frequent tightening up of the bolts is required.

I also believe that creeping of rails is due, to some extent, to the conditions I have above described, *i. e.* by the impact of the 40 rolling stock against the projecting rail head, such rail section is slightly moved longitudinally, and in course of time, under repeated movements of this kind, perceptible creeping of the rail occurs.

45 With the foregoing statement of the art in mind, the primary purpose of my invention is to provide a construction of rail joint by which the surfaces of the contiguous rails are maintained in true alinement, obviating the damage to the adjacent ends and surfaces, removing the cause of pounding of 50 wheels and its resultant damaging effect and reducing the tendency to creeping of the rail.

I accomplish this object by so constructing the rail joint, that upon the approach of the rolling stock on one of the rail sections and depression of the latter, the other rail section will be depressed in a manner to cause the upper surfaces or heads of the two 60 rail sections to remain in surface alinement with each other, as distinguished from the depression of one rail section relatively to the other, which occurs with present constructions. In this manner the rolling stock 65 passes over a practically continuous rail at the joint without striking a projecting adjacent rail section. This, of course, is true irrespective of the direction in which the train travels.

70 The construction of joint at present preferred by me embodies a pair of complementary plates at each side of the rail web, one plate being secured near the end of each rail section at each side of the latter, these 75 plates forming rabbet joints at opposite sides of the rail. The tongues of the rabbet joint on the same side of the rail overlap and project in opposite directions, and the tongues of parallel plates at opposite sides of the 80 same rail section alternate, *i. e.* the tongue of one plate is arranged adjacent the head of the rail and the tongue of the other plate is adjacent the foot of the rail. The construction of the joints is such that as one rail 85 section is depressed the upper tongue of its rabbet joint member will rock upon and exert a downward thrust upon the lower tongue of its complementary joint member, whereby the heads of the rails will be 90 brought together and the bases of the rail slightly separated.

For the purpose of enabling those skilled in the art to clearly understand my invention, I have appended hereto an illustrative 95 sheet of drawing, in which—

Figure 1 is a side elevational view of a complete suspended joint embodying the features of my invention;

Fig. 2 is a similar view with the guard 100 plate removed.

Fig. 3 is a vertical sectional view taken on the line 3—3 of Fig. 1 and looking in the direction of the arrows; and

Fig. 4 is a perspective view of a portion 105° of one of the rail sections with parts of my improved joint carried thereby.

In the drawing, 10 and 11 denote the webs

of the adjacent rail sections, each rail having the usual head 12 and foot or flange 13 supported by the ties 14. Although I have illustrated my invention as applied to 5 a suspended joint, it will be understood that it is equally applicable without modification to a supported joint.

Fitting snugly between the head 12 and the foot 13 of each rail section at each side 10 of the web of the rail, is a joint plate 15 provided with a substantially rectangular rabbet 16, and a tongue 17 projecting beyond the edge or vertical face of the rail section. As will be noted particularly from Figs. 2 15 and 4, the lower face of each tongue 17 is inclined or beveled off at 17^a, thus enabling the tongues to rock, as above suggested, without damage to the metal.

The complementary plates 15 are so arranged 20 that the rabbits on the same side of the web of the rail are oppositely disposed, that is, the rabbet in one plate is adjacent the head of the rail, while the rabbet in the complementary plate is adjacent the foot of 25 the rail, whereby when the rail sections are juxtaposed the tongues on the same side of the rail overlap and project in directions opposite to each other. This construction results in a condition such that the corresponding 30 tongues on opposite sides of the rail project in opposite directions, *i. e.* the upper tongue on the left hand side of the rail (the side toward the observer in Fig. 2) project toward the web 10, while the upper tongue on the right hand side of the rail (the side away from the observer in Fig. 2) projects toward the web 11, the lower tongues on opposite sides of the rail correspondingly projecting in directions 35 opposite to each other.

It will be understood that, in operation, the lower beveled edge 17^a of either upper tongue 17 rocks on the upper plane edge of the lower tongue 17 of the complementary 45 plate 15, while the lower beveled edge of either lower tongue rocks in relation to the foot of the rail and clears the same.

The joints above described may be secured 50 in position by any suitable means. I prefer to provide the joints with guard plates 19 which are held in position by spaced bolts 20, passing through the guard plates, the joint plates 15, and the webs 10 and 11. The bolt holes in the plates 19 are preferably 55 of greater diameter than the bolts, so as to permit the rails to separate the necessary distance without shearing the bolts. I also preferably, although not necessarily, provide the plates 19 with projecting flanges 21 to 60 rest in contact with the ties and be fastened thereto by means of spikes 22. I may, if found preferable, dispense with guard plates 19 and form the flanges 21 directly on the plates 15, whereby spiking of the flanges 21 65 to the ties 14 would secure the joints in de-

sired position, and the spike holes would be sufficiently larger than the spikes to permit longitudinal movement due to expansion.

The operation of the invention will be 70 understood from the following description thereof. Let it be assumed that a train is moving on the rail section 11 in the direction of arrow X. As the train nears the gap 18 between the rail sections, it depresses the section 10, causing the upper visible tongue 17, to rock on the upper plane surface of the lower visible tongue 17, exerting a downward thrust against the latter. As a result of this action, both rail sections are depressed in a manner tending to close the gap 18 and form the upper surfaces of the heads 12 of sections 10 and 11 into a continuous 75 surface. There is a slight depression or angle in this continuous surface at the point of juncture of the rail sections, but neither rail head projects upwardly beyond the other, so that danger of injury to the rail heads, by impact of the wheels against the same, is precluded.

The relative movement of the tongues 17 at the opposite side of the rail is similar to that described and the strains on the rails themselves are transmitted to the joint plates 15, which, owing to their capacity of rocking on each other, are not affected to any appreciable extent by such transmitted strains. It will be understood that, when the rail sections are inclined as described above, the lower edges of each of the lower 90 tongues 17 will clear the foot of the rail sections, thus avoiding binding of these parts.

I desire it to be understood that it is not my purpose to limit the present invention to the precise details of structure herein 105 described, as such details are susceptible of substantial modification without departing from the scope of the invention, as defined by the appended claims.

Having described my invention, what I 110 claim as new and desire to secure by Letters Patent is:—

1. In a rail joint, the combination with rail sections, juxtaposed end to end, of a joint therefor comprising complementary 115 members adapted to rock on each other and to maintain a continuous rail surface at the joint under passage of rolling stock thereover.

2. In a rail joint, the combination with rail sections juxtaposed end to end, of a rabbet joint uniting said sections, said rabbet joint comprising members adapted to rock on each other.

3. In a rail joint, the combination with rail sections juxtaposed end to end, of a joint therefor comprising complementary rabbeted plates at each side of the sections said plates being adapted to rock on each other.

4. In a rail joint, the combination with rail sections juxtaposed end to end, of a joint therefor comprising joint plates at each side of each section, said plates having projecting tongues adapted to rock on each other.
5. In a rail joint, the combination with rail sections juxtaposed end to end, of a joint therefor comprising complemental plates each provided with a rabbet and a tongue, the tongue of one plate extending into the rabbet of its complemental plate and being adapted to rock on said last named plate.
- 10 6. In a rail joint, the combination with rail sections juxtaposed end to end, of a joint therefor comprising complemental plates each having a tongue, the tongues of corresponding plates being adapted to rock on each other.
- 15 7. In a rail joint, the combination with rail sections juxtaposed end to end, of a joint therefor provided with tongues one of which is adapted to rock on and exert a thrust against another.
- 20 8. In a rail joint, the combination with rail sections juxtaposed end to end, of a joint therefor provided with tongues, each having one face beveled, the beveled face of one tongue being adapted to rock on and exert a thrust against the plane face of another tongue.
- 25 9. In a rail joint, the combination with rail sections, of a joint therefor comprising a pair of complemental rabbeted plates at each side of the rail sections, each plate hav-
- ing a tongue projecting into the rabbet of the complemental plate.
10. In a rail joint, the combination with rail sections, of a joint therefor comprising a pair of complemental rabbeted plates at each side of the rail sections, each plate having a tongue projecting into the rabbet of the complemental plate, the tongue and rabbet in a plate on one side of a section alternating with the tongue and rabbet in the plate on the other side of the same section.
- 40 11. In a rail joint, the combination with rail sections juxtaposed end to end, of a joint therefor comprising complemental members adapted to rock on each other, means for securing said members to the respective rail sections, and guard plates adjacent said members and having openings therein through which said securing means 45 loosely project.
12. In a rail joint, the combination with rail sections juxtaposed end to end, of a joint therefor comprising complemental members adapted to rock on each other, bolts securing said complemental members to the respective rail sections, and guard plates lying over said members, said guard plates having openings therein of greater diameter than said bolts and through which 50 55 openings said bolts project.
- In testimony whereof I have affixed my signature in presence of two witnesses.
